United States Patent Office

Des. 200,652
Patented Mar. 23, 1965

200,652

CARD SHUFFLER OR SIMILAR ARTICLE

Morton F. Fisk, 910 5th Ave., New York, N.Y.

Filed July 6, 1964, Ser. No. 80,707

Term of patent 14 years

(Cl. D34—13)

FIG. 1

FIG. 2

FIG. 5

FIG. 3

FIG. 4

FIG. 1 is a front elevational view of a card shuffler or similar article, showing my new design.

FIG. 2 is a top plan view thereof.

FIG. 3 is a side elevational view thereof.

FIG. 4 is a perspective view thereof.

FIG. 5 is a side elevational view thereof showing the side opposite to that shown in FIG. 3.

I claim:

The ornamental design for card shuffler or similar article, as shown.
